United States Patent Office

Des. 183,597

Patented Sept. 30, 1958

183,597

REFRACTORY BLOCK

Horace N. Clark, Pottstown, Pa., assignor to Refractory & Insulation Corporation, New York, N. Y., a corporation of New Jersey

Application December 3, 1957, Serial No. 48,759

Term of patent 14 years

(Cl. D18—2)

Fig. 1.

Fig. 2.

Fig. 1 is a perspective view of a refractory block showing my new design; and

Fig. 2 is a side view of the refractory block.

I claim:

The ornamental design for a refractory block, substantially as shown.
